(57) **CLAIM**

I claim the ornamental design for a cajon drum with removable external snare, as shown and described.

DESCRIPTION

FIG. 1 is a perspective view of the cajon drum with removable external snare showing our new design; FIG. 2 is a front view of the cajon drum with removable external snare of FIG. 1.

FIG. 3 is a rear view of the cajon drum with removable external snare of FIG. 1.

FIG. 4 is a top view of the cajon drum with removable external snare of FIG. 1.

FIG. 5 is a bottom view of the cajon drum with removable external snare of FIG. 1.

FIG. 6 is a left side view of the cajon drum with removable external snare of FIG. 1.

FIG. 7 is a right side view of the cajon drum with removable external snare of FIG. 1, with an open sound hole.

FIG. 8 is a right side view of the cajon drum with removable external snare of FIG. 1, with a closed sound hole.

FIG. 9 is a perspective view of the removable external snare of FIG. 1;

FIG. 10 is a front view of the removable external snare of FIG. 9.

FIG. 11 is a rear view of the removable external snare of FIG. 9.

FIG. 12 is a top view of the removable external snare of FIG. 9.

FIG. 13 is a bottom view of the removable external snare of FIG. 9.

FIG. 14 is a left side view of the removable external snare of FIG. 9; and,

FIG. 15 is a right side view of the removable external snare of FIG. 9.

The broken lines are included for the purpose of illustrating the environmental structure and form no part of the claimed design.

1 Claim, 9 Drawing Sheets
